UNITED STATES PATENT OFFICE

MICHAEL BURG, OF BALTIMORE, MARYLAND

EXTENSION TABLE

Application filed August 19, 1931. Serial No. 558,001.

This invention relates to extension tables. In most extension tables either no provision is made for extra legs to support the table when extended or, if extra legs are provided, such legs have to be moved into and out of the table top supporting position by hand. A so called "gate legged table" may be taken as an example of tables with movable supplemental legs.

One important object of the present invention is to provide an improved form of extension table wherein supplemental legs are provided which automatically move into and out of table top supporting position with the opening and closing movements of the table.

A second important object of the invention is to provide an improved form of extension table having automatically movable supplemental legs which are housed out of sight while the table is closed.

A third important object of the invention is to provide an improved form of extension table wherein the extensions of the top are housed beneath the main top portion when the table is closed and carry supplemental legs which are also housed beneath the main top in horizontal position while the table is closed.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the improved table with one end shown closed and the other shown opened.

Figure 2 is a longitudinal median section with the parts arranged as in Figure 1.

Figure 3 is a bottom plan view thereof partly in section.

Figure 4 is a detail section of one end similar to Figure 2 but with this end of the table in position intermediate between closed and opened positions.

Figure 5 is a section on the line 5—5 of Figure 1.

Figure 6 is a detail view of the central part of one side of the table with the top disassembled from the main frame and raised.

Figure 7 is a detail section on the line 7—7 of Figure 1, the view being to an enlarged scale.

In the embodiment of the invention as here illustrated there is provided a rectangular frame 10 which is supported on four main legs 11 connected at their lower ends by suitable braces 12. Adjacent each corner of the frame 10 and extending upwardly therefrom is a short post 13 and frame or housing sides 14 are secured against the outer side faces of these posts and thus extend along the side members of the frame 10. Extending transversely of the table at the middle portion of the members 14 is a pair of spaced cross members or transverse ties 15 which rest on top of and are secured to the members 14. These ties project slightly beyond the outer faces of the members 14 and thus overhang said members. The main or fixed top 16 of the table rests on the ties 15 and at its central portion is provided on each side with a drop side 17 firmly secured to the under side of said top 16 and provided with notches or recesses 18 to receive the ends of the cross ties 15. Screwed onto the under side of each drop side 17 is a keeper strip 19 which covers the lower faces of the projecting ends of the ties 15 at the respective side and thus the top 16 is held firmly to the frame. It will be noted that the central portion only of the top 16 is thus secured and that the end portions of the top lie spaced above the frame.

Inner guide strips 20 extend between the end members of the frame 10 and have their upper faces flush with the upper faces of said frame members. These guide strips are spaced inwardly from the inner edges of the side members of the frame 10. Intermediate guide strips 21 rest on top of the end members of the frame 10 and are spaced between the respective side members of the frame 10 and the adjacent strip 20. Outer guide strips 22 extend from end member to

end member of the frame 10 and rest on the side members of said frame with their inner faces flush with the inner edges of said frame side members. Each extension top includes 5 an outer or end leaf 23 and an inner leaf 24 hinged together so that the inner leaf may be folded outwardly to lie on top of the leaf 23 when the table is closed or may lie in the same plane as the leaf 23 when the table 10 is open. These two leaves, when folded together just fill the space between the top 16 and sides 14 when the table is closed. Each leaf 23 is fixed on top of the outer ends of a pair of sliding side bars 25 which are connected at their outer ends by a member 26 forming a closure for the space between the posts 13 when the table is closed. The members 25 at one end fit respectively between a guide strip 20 and the guide strip 21 on one 20 side and between the guide strip 21 and the guide strip 22 on the opposite side. The corresponding members 25 for the other end fit in the remaining spaces between the guide strips and thus, when the table is closed, lie 25 alongside of each other. Each of the members 25 rests on an end member of the frame 10 and is provided on its lower edge adjacent its inner end with a cam portion 27 which causes these members to be raised 30 after they have been drawn out somewhat more than half their length in opening the table. Also the inner end of each slide 25 is bevelled off at 28 to engage the bevelled under surface of a respective cam strip 29 35 fixed to the outer side of a respective tie 15 when the slides 28 are pushed in in closing the table. By this means when the table is opened the extension tops are raised to a level with the main top and, when the table 40 is closed, the extension tops are depressed so that they may fit beneath the main top.

Each of the slides 25 has a longitudinal slot 29 therein and extension slides 30 of T-shape in cross-section have their stem portions fitted slidably in these slots. A keeper plate 31 is fixed to the end of the stem of each extension slide and overlaps the upper and lower portions of the respective slide 25 to hold the extension slide in place. The 50 overlapping ends of these keeper plates work in rabbets 32. Stop plates 33 bridge the respective slots 29 at their inner ends and engage stop screws 34 carried by the respective extension slides 30 to limit outward movement of the slides 25. The inner ends of the respective extension slides 30 carry laterally projecting stop pins 35 which, when the slides are pulled fully out in opening the table, engage stop pins 36 projecting downwardly 55 from the ties 15. Between the ties 15 and projecting downwardly below said ties are cam latches 37 which lie in spaced relation to certain of the stops 36. Each of these cam latches has a bevelled under edge forming a 60 cam surface under which the respective pin 65

35 rides just before it engages its coacting pin 36. The end of the latch 37 next the pin 36 is parallel to the pin and thus between each latch and the adjacent pin 36 there is a notch in which the respective pin 35 engages upon the slides being fully drawn out. By reason of this arrangement whenever an end of the table is in its extended position and it is sought to close the same, the extension slide on the side of that end with which the respective latch 37 cooperates will be held in extended position until the main slides at that end are depressed by engagement of the bevels 28 with the cam strips 29. As this occurs the pin 35 which has hitherto engaged the end of the latch 37 will be forced below the latch and the extension slide will be free to move inwardly until its end strikes the cross member 29 at the opposite end. The provision of means for maintaining the extension slide on at least one side of each end in its fully extended position during the first part of the closing movement is highly important as will be now explained.

Hinged to the lower edge of each cross member 26 is a leg plate 38 carrying a pair of legs 39. Pivoted to one of the slides 25 at each end of the table is a leg trip lever 40 having a short arm which engages the head of the T-shaped extension slide 30 on that side, this head being provided with a wear strip 41. The longer arm of this lever 40 carries a laterally projecting pin 42 which engages against the outer face of a leg 39 at this end as seen in Figures 1 and 2. Now, if the table be in extended position at one end and it is desired to close the same, the leaf 24 is folded onto the leaf 23 and the end pushed in. By reason of the extension slide on one side being temporarily held from inward movement the main slide 25 on that side will move in and force the short end of lever 40 to swing outwardly with respect to its pivot, because of its engagement with the extension slide. This causes the long arm of that lever to swing upwardly (see Figure 4) and this movement raises the legs 39 until they are substantially horizontal. The legs will now move inwardly above the frame 10 as the closing movement continues and next the bevels 28 will engage the strip 29 and cause disengagement of the extension slide pin 35 from the cam latch 37 so that the extension slide may now move inwardly. As soon as this disengagement takes place it is followed by the movement of the cam edges 27 over the frame 10 so that the extension top drops and the leaves are slid into place beneath the main top. Obviously the pulling out of the extension end will cause reversal of these steps.

There has thus been provided a simple and efficient device of the kind described and for the purpose specified.

It is obvious that minor changes may be

made in the form and construction of the invention without departing from the material spirit thereof. It is not, therefore, desired to confine the invention to the exact form 5 herein shown and described, but it is desired to include all such as properly come within the scope claimed.

Having thus described the invention, what is claimed as new, is:

- 10 1. In an extension table, a main section having a top, an extension section having a top and being normally housed beneath said top and slideable outwardly therefrom to extended position, legs hingedly connected to 15 said extension section to swing between horizontal position beneath the extension section when closed and vertical position therebeneath when the table is extended, means on the extension section operable by initial closing movement of said extension to swing said 20 legs from vertical to horizontal position, and means to free the last mentioned means upon completion of the initial closing movement.
2. In an extension table, a main section 25 having a top, an extension section having a top and being normally housed beneath said top and slideable outwardly therefrom to extended position, means to elevate the extension section during opening movement to bring the top thereof into the plane of the 30 top of the main section, legs hingedly connected to said extension section to swing between horizontal position beneath the extension section when closed and vertical position 35 therebeneath when the table is extended, means on the extension section operable by initial closing movement of said extension to swing said legs from vertical to horizontal position, and means to free the last mentioned means upon completion of the initial 40 closing movement.
3. In an extension table, a main section having a top, a pair of main slides slidably mounted to move between retracted and 45 housed position beneath said top and extended position projecting from the main section, an extension top carried by said slides, a pair of legs hingedly mounted beneath the outer end of said extension top, an 50 extension slide connected to one of the pair of slides to slide longitudinally thereof, said extension slide being slidably mounted beneath the main section top, latch means carried by the main section for engaging and holding the extension slide from closing movement when extended, means carried by a main slide and operable upon initial closing movement to move the legs to horizontal position beneath the extension top by engagement with said extension slide when extended, and means to free the last mentioned means upon completion of the initial closing movement.
4. In an extension table, a main section 55 having a top, a pair of main slides slidably mounted to move between retracted and housed position beneath said top and extended position projecting from the main section, an extension top carried by said slides, a pair of legs hingedly mounted beneath the outer end of said extension top, an extension slide connected to one of the pair of slides to slide longitudinally thereof, said extension slide being slidably mounted beneath the main section top, latch means carried by the main section for engaging and holding the extension slide from closing movement when extended, a lever pivoted to a main slide and having a short arm bearing against the end of the extension slide, said lever extending alongside of one of said legs, and a pin projecting from said lever and engag- 60
- 65 70 75 80 85 90 95 100 105 110 115 120 125 130
- mounted to move between retracted and housed position beneath said top and extended position projecting from the main section, an extension top carried by said slides, means to elevate said slides as the same are moved to projected position and permit depression thereof as the same are moved to retracted position, a pair of legs hingedly mounted beneath the outer end of said extension top, an extension slide connected to one of the pair of slides to slide longitudinally thereof, said extension slide being slidably mounted beneath the main section top, latch means carried by the main section for engaging and holding the extension slide from closing movement when extended, and means carried by a main slide and operable upon initial closing movement to move the legs to horizontal position beneath the extension top by engagement with said extension slide when extended.
5. In an extension table, a main section having a top, a pair of main slides slidably mounted to move between retracted and housed position beneath said top and extended position projecting from the main section, an extension top carried by said slides, means to elevate said slides as the same are moved to projected position and permit depression thereof as the same are moved to retracted position, a pair of legs hingedly mounted beneath the outer end of said extension top, an extension slide connected to one of the pair of slides to slide longitudinally thereof, said extension slide being slidably mounted beneath the main section top, latch means carried by the main section for engaging and holding the extension slide from closing movement when extended, means carried by a main slide and operable upon initial closing movement to move the legs to horizontal position beneath the extension top by engagement with said extension slide when extended.
6. In an extension table, a main section having a top, a pair of main slides slidably mounted to move between retracted and housed position beneath said top and extended position projecting from the main section, an extension top carried by said slides, a pair of legs hingedly mounted beneath the outer end of said extension top, an extension slide connected to one of the pair of slides to slide longitudinally thereof, said extension slide being slidably mounted beneath the main section top, latch means carried by the main section for engaging and holding the extension slide from closing movement when extended, a lever pivoted to a main slide and having a short arm bearing against the end of the extension slide, said lever extending alongside of one of said legs, and a pin projecting from said lever and engag-

ing the adjacent leg to swing the same, said lever being moved by movement of the main slide relative to the extension slide.

7. In an extension table, a main section having a top, a pair of main slides slidably mounted to move between retracted and housed position beneath said top and extended position projecting from the main section, an extension top carried by said slides, a pair of legs hingedly mounted beneath the outer end of said extension top, an extension slide connected to one of the pair of slides to slide longitudinally thereof, said extension slide being slidably mounted beneath the main section top, latch means carried by the main section for engaging and holding the extension slide from closing movement when extended, a lever pivoted to a main slide and having a short arm bearing against the end of the extension slide, said lever extending alongside of one of said legs, a pin projecting from said lever and engaging the adjacent leg to swing the same, said lever being moved by movement of the main slide relative to the extension slide, and means to free the last mentioned means upon completion of the initial closing movement.

8. In an extension table, a main section having a top, a pair of main slides slidably mounted to move between retracted and housed position beneath said top and extended position projecting from the main section, an extension top carried by said slides, means to elevate said slides as the same are moved to projected position and permit depression thereof as the same are moved to retracted position, a pair of legs hingedly mounted beneath the outer end of said extension top, an extension slide connected to one of the pair of slides to slide longitudinally thereof, said extension slide being slidably mounted beneath the main section top, latch means carried by the main section for engagement and holding the extension slide from closing movement when extended, a lever pivoted to a main slide and having a short arm bearing against the end of the extension slide, said lever extending alongside of one of said legs, and a pin projecting from said lever and engaging the adjacent leg to swing the same, said lever being moved by movement of the main slide relative to the extension slide.

9. In an extension table, a main section having a top, a pair of main slides slidably mounted to move between retracted and housed position beneath said top and extended position projecting from the main section, an extension top carried by said slides, means to elevate said slides as the same are moved to projected position and permit depression thereof as the same are moved to retracted position, a pair of legs hingedly mounted beneath the outer end of said extension top, an extension slide connected to one of the pair of slides to slide longitudinally there-

of, said extension slide being slidably mounted beneath the main section top, latch means carried by the main section for engagement and holding the extension slide from closing movement when extended, a lever pivoted to a main slide and having a short arm bearing against the end of the extension slide, said lever extending alongside of one of said legs, a pin projecting from said lever and engaging the adjacent leg to swing the same, said lever being moved by movement of the main slide relative to the extension slide, and means to free the last mentioned means upon completion of the initial closing movement.

In testimony whereof I affix my signature.

MICHAEL BURG.
